PLUGGING OFF BOTTOM HOLE WATER
UNDER PRESSURERoland E. O'Donnell, Midland, Tex., assignor to
Halliburton Oil Well Cementing Company,
Duncan, Okla.

Application June 3, 1938, Serial No. 211,490

6 Claims. (Cl. 166—1)

This invention relates to the plugging off of bottom hole water in oil wells or the like, and more particularly to methods and apparatus for cementing off bottom hole water under pressure without loading the well with water or mud.

Ordinarily, in the rotary drilling of oil wells as now practiced, mud or other heavy fluid is circulated in the well. A method has recently been devised, however, in which water or oil is used as the circulating fluid, this water or oil having a hydrostatic head at the bottom of the well which is less than that which exists in the formation at that point. Oil or gas from the formation may thus enter the well while the drilling operations are carried on and these fluids flow upwardly in the annular space between the drill pipe and the casing or wall of the well, the discharge or return from the well being controlled by means of a choke or valve. Such a method is described in the patent to Foran et al., No. 2,082,329, granted June 1, 1937, for "A method of drilling and simultaneously exploring oil wells and the like".

The present invention relates to methods of and apparatus for cementing wells which are drilled according to the process described in the above mentioned Foran patent or similar processes. In cementing a well drilled by such a process, it would, of course, be possible to substitute mud for the water or oil used after which the well could be cemented in the usual way. It is desirable, however, not to do this because the mud would then flow into the pay sand or formation and one of the advantages of the pressure drilling process is that this does not take place.

The main object of the present invention therefore is to devise a method for plugging off a water bearing formation in a well drilled by the pressure drilling process without loading the drilling fluid with mud.

It is a further object to devise novel apparatus adapted for use in plugging off a water bearing formation in a well without loading the fluids in the well with mud.

Other objects and advantages reside in certain novel features of the method and apparatus as will become more apparent from the following description taken in connection with the accompanying drawing, in which:

Figure 1 is a schematic representation of an oil well with apparatus constructed in accordance with the present invention therein;

Figure 2 is a vertical cross-sectional view of a special collar adapted to be connected to the tubing in the well shown in Figure 1;

Figure 3 is a vertical cross-sectional view similar to Figure 2 showing the position of the parts after the cement has been pumped therethrough;

Figure 4 is a vertical cross-sectional view of a collar similar to that shown in Figures 2 and 3 but illustrating a modification in the invention; and

Figure 5 is a vertical cross-sectional view of the collar of Figure 4 with a packer mounted therein.

Referring to the drawing in detail, and first to Figure 1, it will be seen that an oil well is there shown at 11, the well being provided with a casing 12 which is cemented in place as illustrated at 13. To illustrate the invention, assume that the well has been drilled to some point beneath the lower end of the casing as illustrated at 14 and that the portion 14 extends through oil bearing formation which may be limestone, as illustrated at 15, and into a water bearing sand such as is illustrated at 16, and that it is now desired to plug off the water bearing formation 16 with cement.

If the portion 14 of the well has been drilled in under pressure by the use of oil as circulating fluid, the pressure in the formation 15 may be greater than the hydrostatic head of the column of oil within the casing, and oil and water from the formations 15 and 16 may be flowing upwardly through the casing and out through a conduit 17, this flow being carefully controlled by a valve 18, commonly referred to in the fields as a "pinch off valve".

To carry out the invention, tubing 19 is lowered into the well through a blow out preventer or some type of tubing head or packing between the tubing and the casing, this being rather diagrammatically illustrated at 20 in Figure 1. Various known tubing heads may be used for this purpose and the construction is preferably such as to permit collars on the tubing to pass therethrough without fluid leaking past the packing, thereof even though subjected to considerable pressure. As shown in Figure 2, the lower joint of the tubing 19 is provided with a special collar 19a, which is provided with a choke member 21 and a steel plug 22. The choke member 21 may be screw threaded within the collar 19a as illustrated.

The lower portion of the choke member 21 is tapered as illustrated and the steel plug 22 is driven therein, effectively preventing the upward flow of fluid through the tubing, while the plug 22 is in place. Beneath the collar 19a, a perforated bull plug 23 is provided, this bull plug serving as means to catch the steel plug 22 when it is

removed from its seat, as will presently be described.

Due to the plug 22 in the collar 19a, it will be seen that as the tubing 19 is lowered into the well, it is empty.

As shown in Figure 1, the top of the tubing 19, after being placed in the well, may be connected to the usual circulating swivel 24 which is supported by means of tackle 25 and which is connected to a pump 27 by means of a hose 26.

With the tubing in the well and connections made as illustrated, hydrated lime water or lime solution is preferably then pumped into the tubing until it is full. Other liquids could of course be used instead of lime water, but its use is suggested because it may tend to aid the cement subsequently pumped into the well to set up and harden. Pump pressure may then be exerted upon the lime water to a pressure sufficient to force the steel plug 22 off of its seat, at which time it moves to the bottom of the bull plug 23 as shown in Figure 3. The valve 18 being carefully manipulated, the lime solution is then circulated up between the tubing and the casing, this lime water serving as a neutralizing and clarifying agent. If desired, a quantity of aquagel may be mixed with water and pumped into the well behind the lime water. It will be understood that during this portion of the process the well will continue to flow and the lime water or aquagel, if it is employed, will be removed from the annular space between the tubing and the casing as the oil from the formation 15 flows upwardly therethrough.

After the well has been conditioned, as noted above, it is desirable that the valve 18 be closed for a period of time, say thirty minutes, before cement is pumped down into the well. The closing of the valve 18 causes the pressure to build up in the formation 15.

After the pressure has built up, the calculated amount of cement necessary to fill the hole in the water bearing formation 16 is mixed and pumped into the well, followed, of course, by some displacing fluid, such as water, and if necessary subjected to sufficient pressure to "squeeze" it some distance into the formation 16.

The cement may be followed by an ordinary cement plug such as is shown at 28 in Figure 4 or a special cement plug 29 may be employed. In either case the cement plug will effect a shut off inside the tubing when it strikes the shoulder on the choke member 21.

Where the special plug 29 is employed, as shown in Figure 3, the opening or bore of the choke member 21 may be provided with threads or other irregular surfaces and the plug 29 provided with a stud 30 which carries dogs 31 adapted to engage the threads in the bore of the member 21 so that the plug 29 is securely latched to the member 21.

If an ordinary cementing plug such as is shown at 28 in Figure 4 is employed, it will remain seated upon the member 21 as long as the pressure above is greater than the pressure below the plug 28.

It will be understood that as the cement is forced downwardly within the tubing the valve 18 will be opened slightly to permit the fluids in the tubing to be displaced.

After the cement has been forced into the formation 16, the tubing must be removed from the well to avoid its being cemented in place.

To prevent a body of cement from remaining in the bull plug 23, as the tubing is initially

raised, it is preferable to provide a check valve 32 and passage 33 in the collar 19a and choke member 21 as illustrated. The valve 32 opens and permits fluid to flow from the exterior to the interior of the collar 19a, to displace the cement as the tubing is raised.

As the tubing is pulled out the desired amount of back pressure is held on the blow out preventer or packing 20 by manipulation of the valve 18. If a cementing plug of the type shown in Figure 3 is employed the tubing will be again sealed after the cement has been discharged therefrom and can be gradually removed from the well. If an ordinary cementing plug is employed, as shown in Figure 4, the tubing can be lifted until the hydrostatic head of the fluid in the tubing which is used to force the cement downwardly is about equal to the formation pressure. At this time the valve 18 is closed a little more, this causing the oil or gas from the formation 15 to lift the fluid in the tubing and the plug 28, thus driving all of the added fluid out of the tubing and carrying the plug to the surface. After the cement plug 28 is removed from the tubing a packer may then be pumped down or lowered into the tubing and secured therein as shown in Figure 5. Any known type of packing device may be employed for this purpose, the arrangement illustrated including an iron body 34 and provided with suitable slips 36 and a rubber packer 37. Any other known suitable packer may be used for this purpose. After the packer 34 is secured in place the tubing can then be pulled out without any oil flowing upwardly therethrough.

With the above process and apparatus it will be seen that the cement can be properly placed within the well even though the formation pressure is high and even though no mud or other heavy fluid is employed to keep the oil or gas in the formation under control.

While the invention has been described in some detail, it is obvious that various changes may be made in the arrangement and construction, as well as in the steps for carrying out the method, without departing from the spirit of the invention or the scope of the annexed claims.

I claim:

1. The method of cementing a well under pressure which includes lowering an empty conduit sealed at the bottom into the well, filling the conduit with wash fluid after it is in position, breaking the seal at the bottom of the conduit, circulating the wash fluid downwardly through the conduit and upwardly on the outside thereof while controlling the pressure therein by regulating the amount of fluid discharged from the well, then pumping into the conduit a quantity of cement slurry and a following fluid until the cement reaches the bottom of the conduit, again sealing the conduit at the bottom and removing the conduit from the well.

2. The method of cementing a well which includes lowering an empty conduit, sealed at the bottom, into the well, breaking the seal, pumping cement slurry through the conduit, again sealing the conduit at the bottom and removing the conduit from the well.

3. The method of placing a liquid in a certain formation at or near the bottom of a well full of fluid while maintaining more than atmospheric pressure on said fluid which includes placing a sealed conduit in the well, breaking the seal in the conduit after the conduit is in place, forcing the liquid to be placed down through the con-

- duit to displace some of the fluid in the well and maintaining pressure on the liquid and fluid during the placing operation by restricting the discharge of fluid from the well.
- 5 4. The method of plugging back a well with cement while maintaining pressure on the fluid therein, which includes placing a sealed conduit in the well, breaking the seal in the conduit after the conduit is in place, pumping cement slurry 10 downwardly through the conduit to displace some of the fluid in the well, maintaining pressure on the slurry and fluid in the well during the displacing operation by restricting the discharge of fluid from the well, again sealing the conduit and removing it from the well.
- 10 5. The method of plugging back a well with cement while maintaining pressure on the fluid therein, which includes lowering a conduit, sealed at or near the bottom, into the well, filling the conduit above the seal with a wash liquid, exerting pump pressure upon the wash liquid to break the seal in the conduit and cause the wash liquid 15 to circulate downwardly through said conduit
- 20

and upwardly on the outside thereof, mixing and pumping into the conduit the calculated amount of cement slurry to fill the desired portion of said well, pumping into the conduit a following fluid until the slurry has left the conduit and again sealing the conduit and removing it from the well, the pressure on the fluid in the well being maintained at all times during the aforesaid steps by restricting the discharge of fluid from the well.

6. Apparatus adapted for use in cementing a well under pressure including a conduit adapted to be connected to tubing or other conduit means to be lowered into a well, said conduit having a choke member therein, said choke member having a tapered seat in the lower portion thereof, a 10 tapered plug tightly fitted within said seat, said conduit and said choke member also having a passageway from the exterior thereof to the interior at a point beneath said choke member and a check valve in said passageway for permitting 15 fluid to flow only from the exterior to the interior thereof.
